UNITED STATES PATENT OFFICE

CARTTER WEAVER, OF PITTSBURGH, PENNSYLVANIA.

INFANT YARD OR PEN.

1,071,283.

Specification of Letters Patent. Patented Aug. 26, 1913.

Application filed September 17, 1912. Serial No. 720,826.

To all whom it may concern:

Be it known that I, CARTTER WEAVER, a resident of Pittsburgh, in the county of Allegheny and State of Pennsylvania, have invented a new and useful Improvement in Infant Yards or Pens, of which the following is a specification.

This invention relates to portable yards or pens for infants.

10 The object of the invention is to provide an improved folding and adjustable yard or pen, in which the infant may be placed for protection, and which can be adjusted within limits to any desired size and may 15 be collapsed or folded to enable it to be compactly stored when not wanted for use.

The invention comprises the construction and arrangement of parts hereinafter described and claimed.

20 In the drawings Figure 1 represents a plan view of a pen or yard constructed according to my invention, the full lines indicating the same opened in contracted position, and the dotted lines indicating the 25 same expanded; Fig. 2 is an end elevation of the pen or yard illustrated in Fig. 1; Fig. 3 is a side elevation, and showing the same in open extended position; Fig. 4 is a plan view of the pen or yard folded or col- 30 lapsed for packing or storage; Fig. 5 is a cross section on the line 5—5, Fig. 1; Fig. 6 is a detail view of a latch; and Fig. 7 is a detail cross sectional view of a bumper foot.

35 The pen or yard shown in the drawings comprises two members A and B, which are of exactly the same construction, it, therefore, being necessary to describe in detail but one thereof. Each member comprises 40 oppositely disposed side walls 1 and 2, which are arranged in parallelism with each other. Both members comprise upper and lower horizontal rails 3 and 4, which are connected by vertical rods or bars 5, socketed, mortised therein or otherwise secured thereto to form a rigid connection. Said bars or rods are preferably spaced apart at such distances as will prevent an infant 45 from getting out of the pen or yard or injuring himself by reaching therebetween.

50 The side wall 1, at one end is provided with a vertically disposed corner post 6, rigidly connected at its upper and lower ends to the rails 3 and 4, and which is located at

one side of said wall and forms a lateral 55 offset therefrom, as indicated in Fig. 1. An end wall 7 is provided to connect the ends of the side walls 1 and 2. This member comprises upper and lower horizontal rails 8 and 9, connected together by vertical rods 60 or bars 5, as in the case of the side walls 1 and 2, and is divided intermediate its ends at the point marked 9, into two sections which are hinged together by hinges 10, placed on the outside of the upper and 65 lower rails. The rails 8 and 9 of the end member are connected at one end by hinges 11, to the corner post 6, said hinges being placed on the inside of the pen or yard, as shown in Fig. 1. At their other ends rails 70 8 and 9 are connected by hinges 12 to the ends of the horizontal rails of the side wall 2, said hinges being placed on the inside of the pen or yard as shown.

The two members A and B of the pen or 75 yard are adjustably secured to each other in such manner as to permit expansion and contraction of the pen or yard in one direction. For this reason the side wall 1 of each of the members is placed in parallelism with the side wall 2 of the other member, and suitable connections are provided for slidably securing the walls 1 and 2 to each other. As shown in Fig. 1, the upper rails of the walls 1 are provided with U-shaped yokes 15 secured near the ends thereof and embracing the upper rails of members 2. Similarly, members 2 are provided at their ends with U-shaped yokes 16 which are secured thereto and embrace the upper 85 rails of members 1. The lower rails of the two side walls are connected in like manner by means of U-shaped yokes 17, which are secured to the respective lower rails and embrace and extend under the same. 95

In normal opened position, the parts occupy the positions shown in Fig. 1 with the halves of the end walls abutting each other at their ends, at the points 9. Suitable latches or hooks 19 are pivotally secured to the upper rails of the end walls at 20 and engage pins 21 on the mating sections thereof, so that when opened the end members can be rigidly locked and secured in the positions shown in Fig. 1. The pen or yard 100 may be expanded in a direction parallel to the length of the side walls 1 and 2 by grasping either of the members A or B and

moving it with respect to the other member, in which case walls 1 and 2 slide lengthwise on each other. In this manner it may be opened to the position shown in dotted lines in Fig. 1, further opening movement being prevented by the engagement of the yokes 15 and 16 with each other, these yokes forming stops to prevent entire separation of the two members of the pen or yard.

10 The bottom rails 4 and 9 of the side and end members are provided with projecting feet or blocks 26, to rest upon the floor and support the frame. These blocks space the lower rails above the floor and give a free space within which the lower yokes 17 may slide during adjustment of the yard without contacting the floor and marring or injuring the same. The feet or blocks 26 may be of any suitable shape and of any material, but preferably, and as shown, will be rubber bumpers suitably secured to the rails and hollowed out to exert a gripping or suction effect upon the floor and act as non-slip devices. The non-slip devices also act as locks or stops to hold the two members of the pen or yard in position when adjusted. The device being opened to the proper size is placed upon the floor, when the friction between the feet or blocks 26 and the floor is sufficient to prevent an infant within the pen or yard from accidentally changing the relation of the members to each other. The pen or yard may also be folded or collapsed, as indicated in Fig. 4, to thereby permit it to be stored away for later use. The latches 19 are swung back and the end walls 7 folded inwardly, the members A and B being adjusted with reference to each other to the smallest size of the pen or yard. By folding in the end walls 7 as described, the parts are brought into the positions shown in Fig. 4, in which case the walls 1 and 2 lie side by side or overlap and the folded end walls 7 are along the center line of the folded pen or yard. The end walls 7 at one end are hinged to the offset corner posts 6 and this permits them in folding to be brought into parallelism with the side members 1 and 2. It will also be observed that the other ends of the end members 7, in the form shown, project beyond or overlap the ends of the side members 2, as at 25. While the joint between the end and side members at these points may be the usual mitered joint, it is preferred to have the end members overlap in the manner stated, since this construction permits the folded pen or yard to be placed on end for storing it away if desired.

60 The pen or yard described is of simple construction and can be readily stored beneath an ordinary couch or placed on end behind a door. It can be made comparatively light so as to be easily handled by the average housewife. When opened up it may be made small or large to suit the size of the

space within which it is used and will thus accommodate itself to rooms of different size.

What I claim is:

1. An infant's yard or pen comprising side and end members, said side members being provided with adjustable connections arranged to permit said yard or pen to be expanded or contracted in a direction parallel to the length of said side members, and means on said members arranged to contact with the floor or support and prevent expansion or contraction of said yard when in normal position thereon. 70

2. An infant's yard or pen comprising side and end members, said side members being provided with adjustable connections arranged to permit said yard or pen to be expanded or contracted in a direction parallel to the length of said side members, and anti-slip devices on said members arranged to contact with the floor or support and thereby normally prevent expansion or contraction of said pen or yard. 75

3. An infant's yard or pen comprising side and end members, said side members being provided with adjustable connections arranged to permit said pen or yard to be expanded or contracted, and said end members being hinged intermediate their ends to thereby permit said yard or pen to be folded or collapsed. 90

4. An infant's pen or yard comprising two members having side walls slidably connected together, said members also having end walls hinged intermediate their ends on the outside of said pen or yard, and hinged at their ends to said side walls and arranged to fold inwardly to thereby collapse said pen or yard. 100

5. An infant's pen or yard comprising two members having side walls slidably connected together, said members also having end walls comprising sections hinged together at their inner ends on the outside of said pen or yard, said sections being also hinged at their opposite outer ends to said side walls and arranged to fold inwardly to thereby collapse said pen or yard, and means for rigidly securing the sections of each of said end members in open position. 110

6. An infant's pen or yard comprising two members having side walls slidably connected together, said members also having end walls comprising sections hinged together at their inner ends on the outside of said pen or yard, said sections being also hinged at their opposite outer ends to said side walls and arranged to fold inwardly to thereby collapse said pen or yard, and means for rigidly securing the sections of each of said end members in open position, comprising a latch on one of the sections of each member, and a co-operating member therefor on the companion section. 120

7. An infant's pen or yard comprising two members each having side and end walls, one of the side walls of each member having a lateral offset, said end members comprising sections hinged together on the outside of said pen or yard, one of said sections being hinged on the inside of said pen or yard to said offset, and the other section being hinged at its end to the other side wall, the side walls of said members being slidably connected together, and said pen or yard being adapted to collapse with the end members folded inwardly into parallelism with said side members.
- 15 8. An infant's pen or yard, comprising two members each formed of top and bottom horizontal rails and a series of vertical connecting bars or rods, each member having side and end walls, the side walls of said members overlapping each other, U-
- shaped yokes secured to the rails of the side walls of each member, each top rail yoke embracing the companion rail of the overlapping member above the same, and each bottom rail yoke embracing the companion rail of the overlapping member below the same, said yokes being arranged to contact when the pen or yard is expanded lengthwise and prevent separation of the members from each other, and bumpers on the bottom rails arranged to space the same above the floor or support and provide a free sliding space for said bottom yokes.
